UNITED STATES PATENT OFFICE.

CHARLES TIBBOTT, OF CLEVELAND, OHIO, ASSIGNOR TO THE STANDARD PARTS COMPANY, OF CLEVELAND, OHIO, A CORPORATION OF OHIO.

METHOD OF SWAGING AND STRAIGHTENING TUBING AND MECHANISM FOR USE THEREIN.

1,287,791.

Specification of Letters Patent. Patented Dec. 17, 1918.

Application filed February 28, 1917. Serial No. 151,418.

To all whom it may concern:

Be it known that I, CHARLES TIBBOTT, a citizen of the United States, and a resident of Cleveland, county of Cuyahoga, and State of Ohio, have invented a new and useful Improvement in Methods of Swaging and Straightening Tubing and Mechanism for Use Therein, of which the following is a specification, the principle of the invention 10 being herein explained and the best mode in which I have contemplated applying that principle, so as to distinguish it from other inventions.

As is well known, more or less difficulty 15 is encountered in feeding tubing through swaging machines for the purpose of reducing the diameter of such tubing, for it is necessary that the stock should be rotated, if a uniform reduction in such diameter and 20 a smooth finish is to be secured. The present invention has as its object the provision of means for automatically feeding the tubing, or other similar stock through the swaging device proper, and at the same 25 time automatically effecting and controlling the rotation thereof in such a manner as to produce a satisfactory product. To the accomplishment of the foregoing and related ends, the invention, then, consists of 30 the steps and means hereinafter fully described and particularly pointed out in the claims.

The annexed drawing and the following description set forth in detail certain steps 35 and mechanism for carrying out the invention, such disclosed means constituting, however, but one of various ways in which the principle of the invention may be used.

In said annexed drawing:—

40 Figure 1 is a side elevational view of a combined tube-swaging and straightening machine embodying my present improvements; Fig. 2 is an end elevation of the same, as viewed from the left in Fig. 1; Fig. 3 is an end elevation of one of the 45 feeding devices, which form a feature of such machine, taken by itself; Fig. 4 is a side elevational view of such device; Fig. 5 is a plan view of the same; while Figs. 6, 50 7 and 8 are sections taken on the planes indicated by the lines 6—6, 7—7, and 8—8, respectively, Fig. 5.

Referring first to the general assembly 55 of the machine as illustrated in Fig. 1, the

swaging device proper is contained in the 55 housing 1 and being of familiar construction is not illustrated in detail. It will suffice, in other words, to state that it consists of a series of hammers, which are successively actuated inwardly to strike blows 60 on the tubing passed centrally through such housing, these successive hammer blows not only having the swaging effect, whereby the diameter of the tube is reduced, and its exterior highly polished, but also having a 65 tendency to rotate the stock in the direction in which the hammers successively strike such tubing. Actuation of this swaging device is secured by means of a tubular driving shaft 2, journaled in suitable bearings 3, and driven by means of a belt 4 passing over a pulley 5 mounted on such shaft, intermediately between such bearings.

Two feeding devices 6, according to the present design, are employed in conjunction 70 with such swager, one at each end, as shown in Fig. 1. Each such device is driven through sprocket chain 7 from a counter shaft 8 journaled in suitable bearings 9 disposed to one side of the main shaft, and 75 driven from such main shaft through the medium of a belt 10 and pulleys 11 and 12, as clearly shown in Fig. 2.

Each such feeding device (see Figs. 3, 4 and 5) comprises a pair of similar, peripherally grooved feed rolls 15, the spindles 16 of which are journaled in the free ends of similar arms 17 that have their opposite ends pivotally secured to a hollow supporting member 18 by means of stud-bolts 19, 85 one on each side of the latter, passing through ears 20 on said arms. Compression springs 21 are held against such arms, intermediate between their ends, by means of nuts 22 on threaded studs 23 projecting 90 oppositely from the hollow member 18, whereby the rolls 15, it will be seen, may be caused to grip a tube, or other article, that extends through such member, with any desired degree of pressure.

On opposite ends of the spindles 16, are mounted spur-gears 24, that respectively mesh with other spur-gears 25 mounted on the same bolts 19, that secure the arms 17 to the hollow member 18, these bolts being 105 suitably formed to provide the necessary spindle-bearing, while attached to each of said last-named spur-gears, is a bevel gear 26.

with its face directed inwardly, that meshes with a fixed bevel-pinion 27 of annular form. The latter surrounds said tubular member and is attached to one of the two standards 28 in which the said hollow member, with all the parts carried thereby, is rotatably supported. One end of said member projects through the adjacent standard to receive the sprocket-wheel 29, by means of which the device is driven from the countershaft 8 previously referred to. The device as a whole, save for this sprocket-wheel, is inclosed in a suitable housing 30 in the assembled condition of the machine, as illustrated in Figs. 1 and 2.

From the construction of the feeding device, as just described, it will be seen that upon rotation of the hollow member 18, through the medium of sprocket-chain 7, the feed-rolls 15 will be driven, by means of the spur and bevel-gears connecting them with the stationary bevel-pinion 27, at a rate of speed depending upon the rate of rotation of the device as a whole. The rotation of these devices, it will accordingly be seen, is effective not only to rotate the stock, but also simultaneously to feed the same forwardly, both devices being geared, of course, to feed in the same direction, and at the same rate of speed.

The rate of rotation of the stock, however, as determined by the rate of rotation of these devices, is designed, by a proper selection of gear ratios, to be slower than that which would normally be produced by the action of the swaging machine 1, if the latter were operating by itself. In this way, it will be seen that, incidentally to the automatic feeding of the stock through the swaging device proper, the stock is rotated in the same direction as the latter would tend to rotate it, but at a lower rate of speed. This avoids the difficulty which arises, as hereinbefore described, where the stock is held entirely against rotation, or where it is left free to rotate with the swinging device. At the same time, the operator is relieved from the very great strain of holding the tube or other article being swaged, and manually directing the same through the machine as well as regulating its rate of rotation. Uniformity in the finished product is of course another valuable result achieved by the foregoing arrangement of mechanisms.

Other modes of applying the principle of my invention may be employed instead of the one explained, change being made as regards the means and the steps herein disclosed, provided those stated by any one of the following claims or their equivalents be employed.

I therefore particularly point out and distinctly claim as my invention:—

1. The method of swaging tubing and like articles, which consists in introducing the

same into a swaging device of the kind adapted to impart a rotary movement to such article, and simultaneously feeding such article longitudinally through said device and rotating the same at a controlled rate different from that which said device would impart thereto.

2. The method of swaging tubing and like articles, which consists in introducing the same into a swaging device of the kind adapted to impart a rotary movement to such article, and simultaneously feeding such article longitudinally through said device and rotating the same at a controlled rate slower than that which said device would impart thereto.

3. In mechanism of the character described, the combination with a swaging device of the kind adapted to impart a rotary movement to an article introduced therein; of feeding mechanism adapted simultaneously to feed such article through said device and impart an independent rotary movement thereto.

4. In mechanism of the character described, the combination with a swaging device of the kind adapted to impart a rotary movement to an article introduced therein; of feeding mechanism adapted simultaneously to feed such article through said device and impart an independent rotary movement thereto, said feeding mechanism being geared to thus rotate such article at a slower rate than said device would impart thereto.

5. In mechanism of the character described, the combination with a swaging device of the kind adapted to impart a rotary movement to an article introduced therein; of a pair of feeding mechanisms alined with said device, one on each side thereof, said mechanism being adapted to grip and positively rotate such article at the same time that it feeds the same longitudinally through said device.

6. In mechanism of the character described, the combination with a swaging device of the kind adapted to impart a rotary movement to an article introduced therein; of a pair of feeding mechanisms alined with said device, one on each side thereof, said mechanisms being adapted to grip and positively rotate such article at the same time that they feed the same longitudinally through said device, and said mechanisms being geared thus to rotate said stock at a slower rate than said device would impart thereto.

7. In mechanism of the character described, the combination with a swinging device of the kind adapted to impart a rotary movement to an article introduced therein; of a pair of feeding mechanisms alined with said device, one on each side thereof, each of said mechanisms comprising a positively

rotated hollow member through which the article passes, rolls carried by said member adapted to grip such article, and gearing adapted to rotate said rolls incidentally to 5 rotation of said member.

8. In mechanism of the character described, the combination with a swaging device of the kind adapted to impart a rotary movement to an article introduced therein; 10 of a pair of feeding mechanisms alined with said device, one on each side thereof, each of said mechanisms comprising a positively rotated hollow member through which the article passes, rolls carried by said member

adapted to grip such article, and gearing 15 adapted to rotate said rolls incidentally to rotation of said member, the gearing connections to said members being arranged to rotate the same, and thus the article gripped by said rolls, at a rate slower than said device would impart thereto. 20

Signed by me, this 24th day of February, 1917.

CHARLES TIBBOTT.
